[57] CLAIM

The ornamental design for a personnel evacuation body harness, as shown and described.

DESCRIPTION

FIG. 1 is a perspective view looking down and to the left at the right rear corner of a personnel evacuation body harness showing my new design;

FIG. 2 is a rear elevation thereof;

FIG. 3 is a left side elevation thereof;

FIG. 4 is a front elevation thereof;

FIG. 5 is a top plan view thereof; and,

FIG. 6 is a bottom plan view thereof.

The left side elevation is a mirror image of the right side elevation shown.
